UNITED STATES PATENT OFFICE.

OLIVER PEARL, OF LAWRENCE, MASSACHUSETTS.

IMPROVEMENT IN FLIERS OF SPINNING-MACHINES.

Specification forming part of Letters Patent No. 37,702, dated February 17, 1863.

To all whom it may concern:

Be it known that I, OLIVER PEARL, of Lawrence, in the county of Essex and State of Massachusetts, have invented an Improvement in Fliers of Spinning-Frames; and I do hereby declare that the following is a full and exact description thereof, reference being had to the accompanying drawings, and to the letters and figures marked thereon.

Figure I is a view of the flier, with the spindle, bobbin, and whirl; Fig. II, plan of top of flier; Fig. III, section of old and new flier-arms; Fig. IV, plan of base of flier; Fig. V, area of surface of flier; Fig. VI, section and elevation of flier-arms.

My improvement in fliers relates to certain changes in their construction and form, by which several important advantages are attained, viz: diminution of the resistance of the air when the flier is revolving, increased stiffness and strength of the flier, an increase of the quantity of yarn that can be put upon the bobbin, also a reduction of the weight of the flier in consequence of its increased stiffness. It is intended mainly for use in a throttle-frame with the spindle termed the "dead-spindle," in which the bobbin that contains the yarn, and also the spindle, are nearly stationary, while the flier, which draws, twists, and winds up the yarn, revolves around the spindle. In cotton-mills using this system of spinning the power to drive the flier is found to be a very large proportion of the whole amount required for the machine, this result being due to its weight, its high velocity, the resistance of the air, and the production of the twist. It therefore becomes a matter of great importance that the flier be made to combine strength with lightness, and at the same time present as small a surface as possible to be resisted by the air when it is revolving.

In Fig. I, A represents the spindle, which is held in a vertical position by suitable bearings, the bottom of the spindle resting upon a transverse rail, which raises and lowers the bobbin H, that is supported upon the bottom E, resting upon a shoulder formed upon the spindle at F. The flier K I J is turned by a band applied to the whirl B, the upper part of the whirl being made with a square shoulder, c, which fits a square aperture, D, Fig.

III, in the bottom of the flier. To each end of the horizontal piece J the vertical arms I I' are attached. They are about eight inches in length, and are bent inward at the top K, and brazed to the flier-nose L, Figs. I and II, in such a position that the flat sides are in the direction of a tangent to the bobbin, and the edges are presented to the air in the direction of the rotation. The flier-nose is circular, and runs in a bushed bearing in the top rail, M. The thread R, as it is spun, passes through a small hole, Q, in the nose L, then around one of the arms of the flier, then under the guide-wire o or o', from which it is wound upon the bobbin H. I make the arms of the flier I I' of swaged iron, flattened from the circular form of the wire N, Fig. VI, to the form shown at I, the wire being flat on both sides and having semicircular or rounded edges. The fliers revolve in the direction shown by the dotted lines in Fig. III. The difference in the area presented to the air is shown in Fig. V, the square T being the total area of the flier-arms I I' and the square U the area of the common arms of round wire, N N'. The velocity of the flier is about five thousand revolutions per minute, or thirty-two miles per hour; consequently the resistance of the air is very great, and the reduction which is effected of thirty-five per cent. of the area of the flier in the direction of its rotation results in a great saving of power.

The flier is made of the common iron wire, untempered. By swaging or compressing the wire into the flattened or oval form it becomes more elastic, and its strength is much increased.

A great many fliers of the ordinary construction are bent, and destroyed by being accidentally struck near the middle, while fliers on my plan may be instantly stopped by an iron bolt or rod without injury.

It is obvious that if formed as herein described the flier may be made of a smaller and lighter wire, and at the same time possess equal strength and stiffness, the reduction in weight being from ten to twenty per cent., according to the required size of the flier.

As the space between the flier-arms is enlarged by flattening the wire, the bobbin can be of greater diameter, and thus contain more yarn. The space occupied by a machine is

also reduced, for, as the fliers are of less diameter, the spindles can be set nearer to each other.

What I claim, and desire to secure by Letters Patent, is—

The combination of the nose or upper bearing of the flier with the sides or arms, made of flattened wire, and brazed or attached to

the nose, so as to be nearly in a tangent to the bobbin, and present the thin edge of the arm to the air when revolving.

OLIVER PEARL. [L.S.]

In presence of—

JOHN K. TARBOX,
HENRY J. COUCH.
